UNITED STATES PATENT OFFICE.

JESSE M. PORTER, OF CUYAHOGA FALLS, OHIO, ASSIGNOR OF ONE-HALF TO DUNCAN R. McAFFEE, OF CUYAHOGA FALLS, OHIO.

SHIPPING CRATE OR CASE.

No. 909,664.

Specification of Letters Patent.

Patented Jan. 12, 1909.

Application filed July 13, 1907. Serial No. 383,590.

To all whom it may concern:

Be it known that I, JESSE M. PORTER, a citizen of the United States, residing at Cuyahoga Falls, in the county of Summit 5 and State of Ohio, have invented new and useful Improvements in Shipping Crates or Cases, of which the following is a specification.

This invention relates to improvements in 10 shipping crates or cases, comprehending specifically a crate or case adapted for shipping various kinds of fruits and vegetables, bottled goods and beverages, and various other articles, and which shall be strong and 15 durable in construction, light in weight, and inexpensive of production.

The object of my invention is to provide 20 a novel construction whereby a crate or case embodying these desirable advantages may be manufactured from a cheap material, such as strawboard, and shall be stiff and strong enough to prevent buckling or breaking and sustain the rough wear and uses to 25 which containers of this character are customarily subjected.

The invention consists of the features of 30 construction, combination and arrangement of parts hereinafter fully described and claimed, reference being had to the accompanying drawings, in which:—

Figure 1 is a perspective view of the body 35 of a shipping case or crate embodying the invention. Fig. 2 is a longitudinal section thereof. Fig. 3 is a plan view of the paper blank from which the body is made. Fig. 4 is a section through a portion of the blank 40 showing the form of the crimp on the fold line between adjacent sections. Fig. 5 is a plan view showing the angle construction 45 of the angle formed when the sections are bent into form along the line of the crimp.

In carrying my invention into practice, a 50 box or receptacle of rectangular or oblong rectangular form is provided and comprises a bottom 1, side walls 2 and end walls 3, made from the form of blank shown in Fig. 3, cut out from waterproof strawboard or some other suitable equivalent strong, stiff and durable paper or material. The side walls 2 are 55 bent at right angles to the bottom and provided along their end edges with inwardly extending flanges 4 which lap over upon the inner sides of the end walls 3, which are formed along their end edges with corre-

sponding flanges 5, the flanges 4 being secured to the walls 3 and the flanges 5 to the walls 2 by staples or rivets 6, thereby fastening the walls firmly and securely together at the corners of the box. It will be observed that this construction forms a double fastening connection at each corner, which adds materially to the strength and stability of the box. The end walls 3 are provided with hand holes formed by slitting the same segmentally, as indicated at 7, leaving flaps 8, adapted to be turned inwardly along their upper marginal edges denoted by the dotted lines 9, the flaps serving to normally close the openings so formed, while being capable of being readily bent inward to permit of the insertion of the hands in grasping, lifting and transporting the box. When the flaps are turned inwardly, they also serve as guards forming smooth surfaces against which the fingers or palms of the hands may bear to prevent chafing or indentations of the flesh liable to be caused by contact of the hand with a narrow upper wall or surface liable to be roughened by frequent handling.

In order to enable the box to be formed from a single piece of material, as represented by the blank in Fig. 3, without weakening the material by slitting it along the lines of bend or fold at the intersections of the portions of the blank, the material composing the blank is crimped between the meeting edges of the several sections of the body of the blank and between the side and end walls and their flanges. These crimps are produced preferably by the action of beading rolls 90 whereby the material is displaced to form upon the inner face thereof a narrow groove or channel, the displaced portion of the material being off-set externally in the form of a rib or bead, as clearly illustrated in Figs. 95 4 and 5. The respective portions of the blank are then bent at right angles to form the completed box so that at the junction of all the portions angular corners 11 will be produced, such angular corner portions being disposed diagonally or obliquely to the adjacent right angularly disposed portions or walls. By this construction, the blank is adapted to be folded to form the body of the box without bending it at a sharp angle and 100 rendering it liable to break or weakening it along the lines of fold by scoring, and a corner or junction angle is at the same time 105

- provided which materially strengthens and stiffens the box at all the corner portions and points of junction of the walls with each other, thus increasing the strength and durability of the box to a marked degree. This is an important feature of my invention, as by its use the box may not only be more easily and conveniently bent or folded into shape but the beaded corners enable a box of maximum strength to be made from a sheet material of the character mentioned, without the fragility of boxes of this kind heretofore devised. As a result of the employment of the beaded joints and double corner fastenings, a box is provided which is strong, stiff and durable enough to withstand the roughest kind of usage without liability of buckling or collapsing while in storage or transit.
- 20 Runner strips 12 of wood or other suitable material are secured to the bottom of the box and extend longitudinally thereof. These strips hold the box spaced a desirable distance from the surface of the floor or ground, and also enable the box to be slid without liability of injury.
- If desired, partitions 13 and 14 of any preferred type and arrangement may be provided upon the exterior of the box to divide the same into any desired number of cells or compartments for holding boxed or bottled goods of any desired nature. The box without the partitions may, however, be used for storing and shipping purposes, and in prac-

tice any suitable type of cover may be employed.

Having thus described my invention, what I claim as new and desire to secure by Letters Patent is:—

The herein-described improved paper box 40 or crate formed of a single piece of flexible material and comprising rectangular bottom, side and end walls provided with flanges at the side edges thereof, the respective walls being separated from each other 45 and from their flanges by intervening parallel longitudinal crimps formed by outwardly displacing the material to provide grooves upon their interior surfaces and curved beads or offsets upon their exterior 50 surfaces, said walls being bent up at right angles to the bottom along the lines of the crimps between the same and bottom, and said flanges being bent at right angles to the walls along the lines of the intervening 55 crimps, and arranged to overlap the walls at the corners of the box, thus producing strengthening external beads or offsets at the angles of intersection of all portions of the box, and fastenings uniting the flanges 60 and walls at each corner of the box and on opposite sides of the corner angles.

In testimony whereof, I affix my signature in presence of two witnesses.

JESSE M. PORTER.
